UNITED STATES PATENT OFFICE.

ALFRED W. F. GUEST, OF BROOKLYN, NEW YORK, ASSIGNOR TO MERGENTHALER LINOTYPE COMPANY, A CORPORATION OF NEW YORK.

TYPOGRAPHICAL MACHINE.

1,088,415.

Specification of Letters Patent.

Patented Feb. 24, 1914.

Application filed January 27, 1913. Serial No. 744,363.

To all whom it may concern:

Be it known that I, ALFRED W. F. GUEST, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal to 15 form a slug or linotype against the matrices which produce the type characters thereon, and the matrices thereafter returned through a distributing mechanism to the magazine from which they started.

20 More particularly, it relates to machines of the kind illustrated for instance in Letters Patent of the United States, No. 547,633, to P. T. Dodge, wherein the matrices are each formed with a plurality of characters, 25 and means are provided for presenting the matrices at one level or another to the mold, so that the cast may be made from one or another set of the characters thereon. My present improvements are designed to 30 change the level of the matrices for this general purpose, when desired, and to this end I preferably provide the intermediate channel, through which the matrices are transferred, with appropriate shifting or 35 switch mechanism, operable at will.

40 In the accompanying drawings, I have illustrated my invention in preferred form and by way of example, and as applied to a linotype machine, but obviously many 45 variations and modifications may be made therein, and in its mode of application, which will still be comprised within its spirit.

Generally speaking, I desire it to be understood that I do not limit myself to any 50 specific form or embodiment, except in so far as such limitations are specified in the claims.

In the accompanying drawings:

55 Figure 1 is a front view of a portion of the

machine, partly broken away, with my invention applied thereto; Fig. 2 is a perspective view of the intermediate channel, partly broken away; Fig. 3 is a front view of the intermediate channel, partly broken away, 60 and showing the switch in operation; and Fig. 4 is a section, taken substantially on the line 4—4 in Fig. 3.

The matrices X and spacers Y are delivered to the assembler A, and after the line 65 is composed, the assembler is raised to introduce the line between the fingers B, B connected to the slide C, whereby the line is transferred through the intermediate channel D to the first elevator E, by which it is 70 lowered into operative relation to the mold F. The parts and their mode of operation, so far described, are or may be substantially like those presented in the Letters Patent previously mentioned. As in the said Dodge 75 patent, the first elevator E is provided with means for supporting the matrices at different levels, so that one set or another of the characters thereon may be presented in operative relation to the mold. These supporting means are not shown herein, but are 80 or may be of the usual or any desired form.

For purposes of description, it may be assumed that the matrices are all assembled 85 at the same level in the assembler A, and that it is desired to shift them to the elevator E at one or another level, so as to bring the corresponding line of characters into operative relation to the mold F. This determination of level I preferably effect 90 while the line is being transferred through the intermediate channel D. This channel is formed with the customary ledges G, which normally engage under the upper 95 ears of the moving matrices X and thus support them, their lower ears passing under the ledges H therein. If the matrices are transferred to the elevator in this position, which is their lower level, their upper line 100 of characters will be presented to the mold and the slug will be cast therefrom in the manner well understood in the art. However, if it be desired to cast the slug from the lower line of characters, it is necessary 105 to present the matrices to the elevator in their upper position, and this change of level I secure by the devices now to be described.

Connected to the intermediate channel D, and preferably at its end and in proximity to the elevator E, is a pivotally-mounted 110

plate or switch J, which in its normal position (see Fig. 1) constitutes in effect a continuation of one of the ribs H. In these circumstances, and as indicated in Fig. 1, the 5 matrices will pass to the elevator without change of level, as their lower ears will ride under the switch J, and they will be held down thereby. If it be desired to transfer the matrices to the elevator at a higher level, 10 the switch J is turned downward, to the position shown in Figs. 2 and 3, when the lower ears of the matrices will engage over the point thereof and be elevated thereby to their upper position in the elevator E. 15 For the convenient manipulation of the switch J, it is preferably provided with an arm and finger piece K, and a pin L adapted to engage a hole in the channel D to hold the switch in its normal position. 20 Although I have illustrated and described my invention as applied to that style of composition where all the matrices are assembled at a common level, and in connection with means whereby they may be transferred to the first elevator at one of two levels, 25 it will be obvious that I am not limited to such a specific arrangement or mode of operation.

As previously stated, I have illustrated 30 my invention only in preferred form and by way of example, and obviously many variations and modifications in the particular construction, and in the application of its principles to other conditions, will suggest 35 themselves to those skilled in the art, without departure from its scope.

Having thus described my invention, its 40 construction and mode of operation, what I claim and desire to secure by Letters Patent of the United States is, as follows:

1. In a typographical machine comprising plural letter matrices, the combination of means for assembling the matrices at a common level and means for presenting them to 45 the casting mechanism at different levels to bring one or another set of characters into operative position, the said presenting means including an intermediate channel through which the matrices are transferred, and devices coöperating with the matrices to bring 50 them from their common assembled level to the desired level during their passage therethrough.

2. In a typographical machine comprising 55 plural letter matrices, the combination of means for assembling the matrices at a common level and means for presenting them to the casting mechanism at different levels to

bring one or another set of characters into operative position, the said presenting means 60 including an intermediate channel through which the matrices are transferred, and the movable switch J to bring the matrices from their common assembled level to the desired level during their passage through the said 65 channel.

3. In a typographical machine comprising plural letter matrices, the combination of means for assembling the matrices at a common level and means for presenting them to 70 the casting mechanism at different levels to bring one or another set of characters into operative position, the said presenting means including the intermediate channel D and the adjustable switch J, so that in one position of the switch the ears of the matrices will pass thereunder from their common assembled level to one of said levels, and in another position thereof will pass thereover to another of said levels. 75

4. In a typographical machine comprising plural letter matrices, the combination of means for assembling the matrices at a common level and means for presenting them to the casting mechanism at different levels to 80 bring one or another set of characters into operative position, the said presenting means including the intermediate channel D formed with the ledge H and the adjustable switch J, which in one position constitutes a 85 90 continuation of the ledge so that the ears of the matrices will pass thereunder from their common assembled level to one of said levels, and in another position engages beneath the ears of the matrices to elevate 95 them to another of said levels.

5. In a typographical machine comprising plural letter matrices, the combination of means for assembling the matrices at a common level and means for presenting them to 100 the casting mechanism at different levels to bring one or another set of characters into operative position, the said presenting means including the first elevator E and devices to coöperate with the matrices after 105 they have left the assembling means at their common assembled level and deliver them to the first elevator at one or another of said levels.

In testimony whereof I affix my signature in presence of two witnesses.

ALFRED W. F. GUEST.
